Int. Cl. D5—03

Fig. 1

Fig. 2

FIG. 1 is a perspective view of a panel having a textured decorative surface; and

FIG. 2 is a plan view in an enlarged scale, relative to the scale of FIG. 1, of a randomly selected section of the panel, the pattern being continuous over the entire surface of the panel as indicated in FIG. 1.

The characteristic feature of my design resides in the decorative surface of the panel.

I claim:

The ornamental design for a panel, as shown and described.
